UNITED STATES PATENT OFFICE.

OSCAR C. FONTAINE, OF DURANT, OKLAHOMA.

DISINFECTION DEVICE.

Application filed April 11, 1921. Serial No. 460,465.

To all whom it may concern:

Be it known that I, OSCAR C. FONTAINE, a citizen of the United States, residing at Durant, in the county of Bryan and State of Oklahoma, have invented certain new and useful Improvements in Disinfecting Devices, of which the following is a specification.

My invention relates to disinfecting devices.

My object is to provide a device of this character adapted to be held in front of an electric fan, so that the current of air from the fan will catch up the disinfectant, vaporize it, and diffuse it through the room.

Another object is to provide a device of this character in two forms, one form being provided with a shell or casing enclosing the disinfectant, and so constructed that it can be opened to the current of air when the fan is running and closed when it is stopped; and the other form dispensing with the casing and leaving the disinfectant fully exposed to the open air so that it will impregnate the air in a room to an appreciable degree even when the fan is not running, and which may therefore be used in small rooms without a fan.

Still another object is to provide a device of this character adapted to carry a mass of absorbent material heavily charged with the disinfectant solution without the same being in danger of dripping, thus giving better results while the device is at work, and requiring it to be charged less frequently with the disinfectant solution.

Minor objects will appear in the subjoined description.

A leading feature of the invention consists of a reticulated ball provided with removable means for securing the same to the protecting shield of an electric fan, and having a drip pan secured to the under side of the ball; to which ball, if desired, may be added a casing enclosing the ball and adapted to be removably secured to the securing means of the ball, said casing being formed of two hollow shells, with the inner shell secured to the ball, and the outer shell rotatably mounted on the inner shell, said shells being provided with registering inlet and outlet openings for the current of air from the electric fan, the outer shell being provided at its open end with a flared

annular flange for directing the air into the 55 inlet openings of the casing.

The invention consists in certain novel features of construction and arrangement of parts as will be hereinafter described and claimed, reference being had to the accompanying drawings, in which:—

Fig. 1 is a side elevation of my device attached to an electric fan.

Fig. 2 is a sectional view of the device removed from the fan.

Fig. 3 is a view of the reticulated ball removed from the casing; and,

Fig. 4 is a sectional view of a box containing the ball as stored therein when not in use.

The numeral 1 indicates an electric fan having a protecting shield 2 for the wings of the fan. The ball 3 is formed of reticulated material, preferably fine wire, suitably secured at one side to a metallic band 4, said band surrounding an opening in the side of the ball, and provided with an internal thread to receive a screw plug 5 having a hook 6 for engaging the shield 2 of the fan.

The ball has a shallow drip pan 7 secured to its under side preferably by means of a screw 8 rigidly secured to the inside of said drip pan by means of soldering or otherwise, and screwed in through the 85 meshes of the wire. But if desired, the drip pan may be permanently secured to the ball by a few drops of solder instead of by the screw.

The inner shell 9 of the casing is internally threaded at its entrance end to removably receive the flat band 10 which has a central threaded opening for the reception of the screw plug 5 of the ball. This band 10 thus forms a connection between the ball and 95 the inner shell of the casing.

The outer shell 11 of the casing is rotatably held on the inner shell by means of a suitable plug or rivet 12. The two shells of the casing are provided with the registering inlet openings 13 and the registering outlet openings 14 for the passage of air from the fan over the ball.

The outer shell 11 of the casing is provided around its open end with an outwardly 105 flaring flange 15 for directing the air from the fan through the inlet openings 13 into the casing.

The ball is to be filled with absorbent cotton, wool, or the like for holding an ample supply of the liquid disinfectant.

The operation of my device is as follows:—

The ball 3 is filled with a suitable absorbent material and the plug 5 screwed in: the absorbent material is then saturated with the disinfectant, and the ball, by means of the hook 6, is hung on the protecting shield 2 of the fan, where it will be exposed to the blast of air from the fan. If the absorbent material in the ball has been excessively charged with the liquid disinfectant, the drip pan 7 will catch the surplus liquid and keep it from dripping; and will retain it till it is used up by the current of air passing over the ball.

When it is desired to use the casing in connection with the ball, the casing is connected to the ball by means of the band 10, as shown in Fig. 2, and then the flared flange 15 will catch the current of air from the fan and direct it through the inlet openings 13 into contact with the ball as it passes toward the outlet openings 14 in the end of the casing.

The quantity of air passing through the casing may be regulated by a suitable rotatable adjustment of the outer casing 11 to the inner casing, so as to regulate the inlet and outlet openings.

When not in use the inlet and outlet openings are entirely closed.

The movement of the outer shell upon the inner is limited by a small screw or pintle 16 rigidly secured to the inner shell, and projecting out through a slot 17 of the outer shell.

When the casing is not employed, but the ball 3 only is used, I provide a box 18 for the reception of the ball when not in use, so that the same will not be exposed to the

air: for it will be seen that my construction is such that the ball can be used separately, and the casing added if desired. In this way, the device consists essentially of three parts when disassembled—the ball 3, the two shells 9 and 11, and the flat band 10 for connecting the ball with the inside shell.

Having thus described my invention, what I claim as new and desire to protect by Letters Patent is:—

1. In a device of the character described, a hollow ball formed of reticulated material and having inside thereof absorbent material adapted to be moistened with an evaporable fluid, said ball having an opening for the insertion thereinto of said absorbent material and being provided with a drip pan for excess fluid; a band secured in said opening; a plug adapted to be received into said band; and means carried by said plug for engaging the guard of an electric fan.

2. In devices of the character described, a perforated container for absorbent material; a casing for said container, and means for supporting the same in front of an electric fan with the end of the casing next the fan closed, said casing having peripheral openings in its portion adjacent said closed end for the entrance of air from the fan and having openings at its other end for the escape of said air, said peripheral openings being disposed at a sharp angle to the natural line of travel of the current of air escaping from the fan; said casing being provided at the rear of said peripheral openings with a flared annular flange opening toward the fan for directing the air from the fan into said inlet openings of the casing.

In testimony whereof I affix my signature.

OSCAR C. FONTAINE.
